UNITED STATES PATENT OFFICE.

BEULAH TRAUGHER, OF HOUSTON, TEXAS.

CONTAINER.

Application filed October 25, 1927. Serial No. 228,537.

This invention relates to new and useful improvements in a container.

One object of the invention is to provide a container of the character described specifically designed for the purpose of holding soap and similar articles.

Another object of the invention is to provide a device of the character described equipped with means for attaching the container to the margin of a bath tub or wash basin, said attaching means being foldable so as to be out of the way, so that the container can be readily packed and will not occupy unnecessary space.

A further feature of the invention is to provide a container of the character described having a removable top for protecting the contents of the container, and having a perforated bottom for drainage purposes, and provided with a removable supporting bracket by means of which the contents of the container may be readily lifted out.

With the above and other objects in view this invention has particular relation to certain novel features of construction, operation and arrangement of parts an example of which is given in this specification and illustrated in the accompanying drawings, wherein:-

Figure 1 shows a side view of the container as attached to a bath tub, and with the cover removed.

Figure 2 shows a perspective view thereof,

Figure 3 shows a plan view thereof, with the cover removed.

Figure 4 shows a side view of the container showing the hanger in folded position.

Figure 5 shows a vertical sectional view taken on the line 5—5 of Figure 3, and

Figure 6 shows a bottom plan view.

Referring now more particularly to the drawings, wherein like numerals of reference designate similar parts in each of the figures the numeral 1 designates the body of the container, of box-like contour and having the perforated bottom 2 for drainage purposes.

There is an inverted cup like cover 3 removably fitted over the top of the body 1.

There is a bifurcated bracket 4, having the spaced legs 5, 5 which embrace the lengthwise partition 6 which separates the body 1 into two chambers, and the lower end of each leg 5 carries an outwardly extending

ledge, or shelf 7 whereon the bars of soap, 55 or other articles, as 8, may rest. The bracket 4 is supported on the partition 6 and holds the ledges 7 spaced above the perforated bottom 2 so as not to obstruct the perforations thereof. 60

The bracket 4 is formed with a suitable handle 9 by means of which it may be inserted into or withdrawn from, the container body 1. When the soap or other article on the ledges 7 are small and inaccessible the bracket 4 may be lifted out for gaining access to such articles. 65

There is a U-shaped hanger 10 the free ends of whose arms are pivoted to opposite sides of the body 1 and this hanger is bent 70 into a substantially right angular form, as shown, so that when in one position it may be engaged over the margin of a bath tub or wash basin to support the container, and when in another position, will be folded up 75 closely against the container and will not occupy unnecessary space when it is desired to pack the container in a suit case, hand bag or the like.

While I have shown what I now consider 80 the preferred form of the invention it is obvious that mechanical changes may be made therein and equivalents substituted for the parts shown and I hereby reserve the right to make such mechanical changes as 85 may be found practical, or desirable so long as I do not depart from the principle of the invention as comprehended within the scope of the appended claims.

What I claim is:-

1. A device of the character described comprising a box like container having a perforated bottom, a vertical partition therein, a bifurcated bracket having spaced legs which closely embrace and are supported by said partition, a flat horizontally disposed support carried by the lower end of each leg, said supports being open on three sides to expose objects placed thereon, and being spaced above the bottom of the container and being sustained solely by said legs, an upstanding handle carried by the bracket, a cap like cover fitted onto the container and inclosing said bracket and handle. 90 95 100

2. A device of the character described comprising a box like container, a vertical partition therein, a bifurcated bracket having spaced legs which closely embrace and

are supported by said partition, a flat horizontally disposed support carried by the lower end of each leg, said supports being spaced above the bottom of the container and being sustained solely by said legs, said supports being adapted to sustain solid objects and being formed to expose said

objects on the sides and to render them accessible when the bracket is elevated above the container top and an upstanding handle 10 carried by the bracket.

In testimony whereof I have signed my name to this specification.

BEULAH TRAUGHER.
